United States Patent Office

Des. 210,487
Patented Mar. 12, 1968

210,487

LITTER RECEPTACLE

Robert P. Reavis, Statesville, N.C., assignor to Fusion
Rubbermaid Corporation, Statesville, N.C., a corporation of North Carolina

Filed June 20, 1967, Ser. No. 7,524

Term of patent 14 years

(Cl. D49—34)

FIG. 1

FIG. 3

FIG. 1 is a perspective view of a litter receptacle showing my new design.

FIG. 2 is a top plan view thereof.

FIG. 3 is a side elevational view thereof.

The essential features of my design reside in the portions shown in solid lines, the conventional pole and mounting device being shown in broken lines.

I claim:

The ornamental design for a litter receptacle, as shown and described.
